KEY POUCH

Daniel J. Nash, New York, N. Y., and Robert L. Hatfield, East Orange, N. J., assignors to said Daniel J. Nash, New York, N. Y.

Application April 9, 1938, Serial No. 201,050

8 Claims. (Cl. 150—40)

This invention relates in general to key pouches or key cases for normally encasing keys and the like for convenient carriage in the pocket, handbag or the like, and permitting the keys to be projected or pulled from one end of the case for use. A key case of the same general nature is described and claimed in the co-pending application of Daniel J. Nash, Serial No. 196,457, filed March 17, 1938, said case including in general a flexible envelope or cover and a lazy tongs system of links within the cover or envelope for moving a key holder toward and from an opening in the envelope to project and retract keys on the holder through said opening out of and into the envelope.

A prime object of the present invention is to provide a key pouch of the general character described which shall embody novel and improved means for automatically ejecting the keys from an opening in the envelope or cover for use of the keys and for automatically retracting the keys into the envelope or cover after use thereof.

Another object is to provide a key pouch of this character which shall include a case, envelope or cover having a lazy tongs mechanism therein, and novel and improved means for operating the lazy tongs mechanism, whereby said mechanism can be operated by one hand of the user to eject and retract keys through an opening in the case into and out of the case.

Another object is to provide novel and improved automatic means for holding the keys in ejected position for use and for releasing the ejected keys at the will of the operator for retraction thereof into the case after use; to provide a key case of the character described which shall be simple, inexpensive, reliable and durable in construction and operation, and to obtain other advantages and results as will be brought out by the following description when read in conjunction with the accompanying drawing in which

Figure 1 is a plan view of a key case embodying our invention, showing the keys ejected therefrom in dot and dash lines.

Figure 2 is a similar view with the upper portion of the case, envelope or cover removed, and showing the keys within the case.

Figure 3 is a view similar to Figure 2 showing the keys ejected from the case.

Figure 4 is a view similar to Figure 3 showing the side of the mechanism opposite that illustrated in Figure 3.

Figures 5 and 6 are transverse vertical sectional views on the lines 5—5 and 6—6 of Figures 2 and 3 respectively.

Figure 7 is a vertical longitudinal sectional view on the line 7—7 of Figure 4.

Figure 8 is an exploded view showing one of the finger pieces and the associated detent or catch, and

Figure 9 is a fragmentary sectional perspective view of one end of the case, cover or envelope.

The pouch embodying the invention comprises a case, envelope or cover A of any suitable construction having an opening B, preferably at one end. As shown, the case is formed of flexible material such as leather and is composed of two similar pieces 1 secured together in superposed relation at their edges as by stitches 2.

Within the case is a key holding and ejecting mechanism C which is shown as comprising a lazy tongs system of links which includes a plurality of similar links 3. As shown, there are three pairs of the links 3, the links of each pair being connected at one end to the links of another pair as at 30, and the links of each pair being pivotally connected together substantially midway between their ends as at 4. The free ends of the pair of links at one end of the system have pin and slot connections 5 with a key holder 6 that is shown in the form of a plate having a plurality of key holding loops or clips 7 pivotally or otherwise movably connected thereto and to which keys D are attached.

The free ends of the pair of links at the other end of the system are pivotally connected at 8 to the respective actuators or finger pieces 9. As shown, these finger pieces 9 are approximately rectangular blocks of suitable material which are slidably mounted to move toward and from each other in a guide channel 10 which is formed integrally with a supporting plate 11. As shown, the plate 11 has one end returned to form the channel, and the free edge has an inturned flange 12, whereby the finger pieces 9 are held against lateral movement in the guide channel. The pivot connecting the links of the pair which are connected to the finger pieces 9 is in the form of a pin 13 that is slidably mounted in a slot 14 in the supporting plate 11. With this construction, as the finger pieces 9 are pressed toward each other in the guide channel 10, the lazy tongs system of links will be extended as shown in Figure 3 to move the key holder 6 toward the opening B and eject the keys D on the clip 7 from the case through said opening.

For contracting the lazy tongs links so as to move the key holder 6 away from the opening B and retract the keys into the case, we have shown a spring which includes a helical coil 15 having 55

its ends 16 pivotally connected to the joints between two adjacent pairs of links, as clearly shown in Figures 3 and 4. With this construction, the spring normally tends to draw the lazy 5 tongs links together so as to contract the system of links as shown in Figure 2, and at the same time causes the finger pieces 9 to project from opposite ends of the guide channel 10.

The supporting plate 11 is mounted at the end 10 of the case A opposite the opening B, and the edges of the case have openings 17 through which the finger pieces 9 project, as shown in Figures 1, 2 and 9.

With this construction, the key holder 6 and 15 the associated keys D are normally encased as shown in Figure 2. When it is desired to use any of the keys, it is simply necessary to grip the finger pieces 9 between the thumb and index finger of one hand, and press the finger pieces 20 toward each other. This will result in actuation of the lazy tongs links to project the keys D from the case through the opening B as shown in Figure 3. Upon release of the finger pieces, the spring 15 will actuate the lazy tongs links in 25 the opposite direction so as to retract the keys into the case as shown in Figure 2.

In accordance with the invention, means is provided for temporarily holding the keys in ejected position for use. As shown, a spring 30 detent or latch 18 is carried by each finger piece 9, the finger piece having notches 19 in its corners in which are fitted tongues 20 on the corresponding detent. The detent lies between the corresponding finger piece 9 and the main supporting plate 11, and has a head 21 to cooperate with the edge 22 of an opening 26 in the plate 11 as shown in Figures 4, 5 and 6. The head 21 is carried by a spring neck 23 that is formed by slitting the spring metal of which the detent 35 is formed, as indicated at 24. To provide a clearance for operation of the head and neck, the finger piece has a groove 25 to accommodate the neck upon movement of the head 21.

Normally, when the keys are encased, the 45 detent and head are disposed between the corresponding finger piece 9 and the main supporting plate 11, as shown in Figure 5. When the finger pieces are pressed together to eject the keys from the case, the heads 21 of the detent snap upwardly into the opening 26 and engage the edges 22 of the opening so as to hold the finger pieces against movement in the opposite direction under the influence of the spring 15. To release the finger pieces and permit the keys to be automatically retracted into the case, it is simply necessary to press the heads 21 of the detents downwardly or inwardly so as to disengage the edges of the heads from the edges 22 of the opening 26. The portion of the material of the case A 50 overlying the opening 26 is sufficiently flexible to permit the heads 21 to be depressed through the material.

The main plate 18 may be secured in any suitable manner, but preferably the ends of the pieces 55 1 of which the case is formed are wrapped around the channel portion of the plate, and a channel-shaped binder 27, for example of metal, clamps the ends of the material between itself and the plate 11, as shown in Figures 1 and 7. If desired, the plate 11 may be secured to the material of the case by adhesive or by rivets and in many instances the binder 27 may be omitted. Where the binder is used, it is either made flexible or is cut away as indicated at 28 at the zone 60 adjacent the opening 26 in the plate 11.

While we have shown and described the now preferred embodiment of the invention, it should be understood that the details of structure of the case may be widely modified and changed without departing from the spirit and scope of 5 the invention.

Having thus described our invention, what we claim is:

1. A key pouch comprising a case having an opening, a key holder within said case, a lazy 10 tongs mechanism within said case with one end connected to said key holder, and finger pieces connected to the other end of said lazy tongs mechanism and projecting from opposite edges of said case for actuating said lazy tongs mechanism to move said key holder toward said opening and project keys on the holder through the opening, a guide for said finger pieces having a shoulder to cooperate with a detent, and a detent connected to and movable with one finger piece to 15 20 releasably engage said shoulder for holding lazy tongs mechanism in the position for projecting the keys from the case.

2. A key pouch comprising a case having an 25 opening, a key holding and ejecting mechanism in said case including a lazy tongs system of links comprising a plurality of pivotally connected pairs of pivotally connected links, a key holder connected to and movable with one end of said system of links, and actuating means for 30 said system of links to move said holder toward and from said opening and project and retract keys on said holder out of and into said case through said opening, said actuating means including a spring for actuating the links in one 35 direction and finger pieces connected to said links for actuating the links in the opposite direction against the influence of said spring, said spring comprising a loop disposed at one side of said lazy tongs system of links in a plane parallel to 40 the plane of the lazy tongs system and having each end connected to one of the pivotal connections of the ends of said links.

3. A key pouch including an approximately flat case of pliable material having an opening at 45 one end, a key-holding and ejecting mechanism in said case including a lazy tongs system of links comprising a plurality of pivotally connected pairs of links each pair of which consists of two links pivotally connected intermediate their ends, 50 a key holder pivotally connected to the links at the end of said lazy tongs system nearer said opening in the case, a rigid supporting plate mounted in said case adjacent the end thereof opposite said opening, a pair of operating members projecting from the case and movable toward and from each other and operatively connected to the links at the other end of said lazy tongs system whereby to extend said system and move said key holder toward said opening upon 55 movement of said operating members toward each other, and means mounting said lazy tongs system of links and said operating members on said supporting plate.

4. A key pouch including an approximately flat case of pliable material having an opening at one end, a rigid supporting plate mounted in said case and having a guide channel opening at opposite ends through the walls of the case, operating members slidable toward and from each other but otherwise immovable in said guide channel and projecting outwardly from opposite sides of the case, a key holder in said case movable toward and from said opening, a lazy tongs system of links pivotally connected at one end to 70 75

5 said key holder and having a pair of crossed pivotally connected links at its other end, one end of each of which is pivotally connected to one of said operating members whereby said lazy tongs system of links is connected to said supporting plate, said operating members being movable toward each other to extend said system of links and move said key holder toward said opening, and a spring for contracting said system of links to move said key holder away from said opening and project said operating members from the case.

10 5. The key pouch set forth in claim 3 wherein said supporting plate has a slot, and the pivot connecting the links of one pair of links is a pin 15 slideable in said slot upon extension and contraction of said lazy tongs system.

20 6. The key pouch set forth in claim 4 wherein said supporting plate has a slot, and the pivot of said pair of crossed pivotally connected links is a pin slideable in said slot upon extension and contraction of said lazy tongs system.

25 7. A key pouch including an approximately flat case of pliable material having an opening at one end, a flat rigid supporting plate secured in said case adjacent the end opposite said opening, a lazy tongs system of links, operating members connected to one end of said system for extending the system, means securing said end of the lazy tongs system and said operating members

30 on said rigid supporting plate, a key holder connected to the other end of said lazy tongs system to be moved toward and from said opening of the case upon extension and contraction of said lazy tongs system, and means for contracting said lazy tongs system of links. 5

8. A key pouch comprising a case having an opening, a key holder in said case movable toward and from said opening, a lazy tongs system of links connected at one end to said key holder, a supporting plate mounted in said case and having a guide channel opening at opposite ends through the walls of the case, finger pieces slideable in said guide channel toward and from each other and projecting outwardly from opposite 15 sides of the case, each finger piece pivotally connected to the end of one link of the pair of links at the end of the system opposite said key holder, said finger pieces being movable toward each other to extend said system of links and move 20 said holder toward said opening, a spring for contracting said system of links to move said holder away from said opening and project said finger pieces from the case, a spring detent connected to and movable with one finger piece, and 25 a shoulder on said supporting plate to cooperate with said detent for holding said system of links extended.
